CLAIM

The ornamental design for a planter frame and inner planter receptacle therefor, as shown and described.

DESCRIPTION

FIG. 1 is a front perspective view of a planter frame and inner receptacle therefor showing our new design;

FIG. 2 is a top plan view thereof;

FIG. 3 is a bottom plan view thereof;

FIG. 4 is a side elevational view thereof, the inner receptacle being omitted for clarity of illustration.

FIG. 1

FIG. 2

FIG. 3

FIG. 4
